DESK SET BASE

William E. L. Bunn, Fort Madison, Iowa, assignor to W. A. Sheaffer Pen Company, Fort Madison, Iowa, a corporation of Delaware

Filed Nov. 6, 1959, Ser. No. 58,230

Term of patent 14 years

(Cl. D74—1)

The broken line illustration in Figure 1 of the pen and holder therefor is for illustrative purposes only.

I claim:

The ornamental design for a desk set base, substantially as shown and described.
